Patented Jan. 18, 1916.

Inventor:
Thomas W. Irvin
by C. M. Clarendon

UNITED STATES PATENT OFFICE.

THOMAS W. IRWIN, OF PITTSBURGH, PENNSYLVANIA.

SKYLIGHT CONSTRUCTION.

1,168,942.

Specification of Letters Patent. Patented Jan. 18, 1916.

Application filed April 14, 1915. Serial No. 21,337.

To all whom it may concern:

Be it known that I, THOMAS W. IRWIN, a citizen of the United States, residing at Pittsburgh, in the county of Allegheny and State of Pennsylvania, have invented certain new and useful Improvements in Skylight Construction, of which the following is a specification.

My invention relates to improvements in skylight construction, and is particularly designed for the purpose of providing an improved connecting and supporting mechanism for the skylight members, *i. e.*, of plate glass or other similar material.

The invention provides means for supporting the edge portions of the said plates, means for firmly connecting and clamping the plates to the supporting structure, and particularly, to an improved form of cushioning carrier embodying an incorporated gutter, adapted to yieldingly support the plates with facility for tight closure, and relative lateral movement of said elements, providing compensation for movement or displacement of the plates.

The construction in certain preferred forms is illustrated in the accompanying drawings, in which—

Figure 1 is a cross sectional view, partly broken away, of an inclined roof structure embodying the invention. Fig. 2 is a similar sectional view, taken on the line II, II, of Fig. 1. Fig. 3 is a perspective detail view of one of the yielding supporting and gutter embodying members. Fig. 4 is a similar view, showing a modified construction of such member. Fig. 5 is a detail view of the bolt connection.

In general, the skylight construction as a whole is somewhat similar to well-known constructions, in that it utilizes standard shapes and forms of supporting elements, the present invention relating particularly to certain elements as above specified, and as hereinafter more particularly described and claimed.

Referring to the drawings, the skylight plates 2 are slopingly arranged and supported on transverse roof members consisting of plates 3, 3, which are connected by end portions 4 with the central ridge construction 5. Said roof members slope downwardly therefrom at each side and rest at their other ends upon any suitable support, as a main roof structure 6.

Roof members 3 are turned outwardly and

upwardly at their lower portions, as by the wings 7, providing the main gutter channels 8 for carrying off any moisture which may pass downwardly through the joints.

60

Riveted at each side of roof members 3 are the angle members 9, extending outwardly at each side thereof and forming supporting shelves for the gutter bars 10. These bars 10, which are preferably of lead or other soft material, are provided with the flat base adapted to rest upon the upper face of the angle bracket 9, and upwardly beyond said base portion extends a ridge 11 which tapers toward a knife edge 12, upon which the 70 under surface of the plate 2 rests.

65

An inner upstanding leg 13, integral with base 10, extends upwardly at right angles thereto, providing between it and the adjacent face of ridge 11 a continuous gutter 75 cavity *a*. Said leg or wall extends well above the top of the plate so as to insure the collection of moisture in the gutter.

In normal position the wall 13 is spaced slightly away from the adjacent face of roof member 3, as indicated at *b* (Fig. 2), so that the supporting gutter member is thus free to move in either direction laterally with the plate 2, due to its expansion or contraction, vibration, or sagging under the weight 85 of snow or the like, thus providing for a close intimate unchanging relation between the plate and such supporting member at all times.

80

Extending upwardly from the top edge 90 portions of the roof members 3 are the bolts 14, the squared heads 15 of which are in notched engagement with correspondingly shaped apertures 16 in the upper edge portions of said roof members, so as to provide a firm holding engagement for the bolts.

95

Straddled over the upper portions of the roof members is an inner saddle or cap member 17, of sheet copper or other suitable material, the lower edge portion of which at 100 each side is provided with a clamping bar 18 of lead or other similar suitable material, adapted to lie flatly upon the upper faces of the plates 2, at each side, and when drawn down tightly, to provide a closing flashing, 105 and water-tight joint.

At intervals, corresponding to each of the bolts 14, is an outer saddle member 19, of copper, brass, or other suitable non-corrosive material, the bolt 14 extending upwardly through said saddle, and also through member 17. Each of said members

110

is provided with an upwardly extending circular flange 20 and 21 respectively, one nesting within the other, and a securing nut 22 is hollowed out in its interior, as at 23, 5 providing a receiving cavity for the uppermost annular projection 21. By this means, when the nut is screwed down tight, the several parts will be clamped tightly together, and the upwardly extending, partly telescoping terminals 20 and 21 respectively 10 form a water-tight joint adapted to shed any moisture which may gather beneath the nut.

At intervals, extending at right angles to 15 the roof members, and between the adjacent transverse edges of plates 2, I interpose a cross connecting gutter member bar 24 of thin sheet metal, which extends upwardly between the plates, as shown in Fig. 1, and 20 downwardly over the lower plate by an extension 25, whereby to shed the water away from the joint.

The upper portion of the gutter member 24 extends upwardly along underneath the 25 lower edge of upper plate 2, as indicated at 26, sufficiently far to prevent any overflow of water inwardly, thus insuring its being carried off downwardly over the outside surface. Should, however, any water accumulate 30 late and rise inwardly over such portion, it will be collected in the gutter and conveyed laterally and discharged into one of gutters 8 of roof members 3, and be thereby carried off. A similar gutter member 27, 35 of sheet metal, is also laid across between the roof members at the upper end portion of each of the skylight sections, adapted to carry away any moisture and deliver it into the roof member gutters in the same manner, as indicated by the arrows. 40

For the purpose of yieldingly supporting the upper horizontal edge portions of plates 2, I employ a gutter member, similar to that above described, having the base 45 10, ridge 11, gutter a, and inner wall 13, lying upon the supporting element 5' of the ridge piece 5, and adapted to yieldingly support the upper edge of the plate and to come and go with it, in the same manner 50 as above described.

At the lower portion of the structure, I employ a similar yielding support having a base 10', a ridge 11', and a downwardly extending lip 13', adapted to lie along a 55 transverse supporting shelf 28 which is incorporated with the end structure of the sloping roof. Such portion of the roof is also provided with a terminal retaining bar or plate 29, and a closing plate 30 having 60 an opening 31, through which water may pass outwardly from the channels 8 upon roof 6 or elsewhere, as will be readily understood.

The construction and operation of the invention will be readily understood from the

foregoing description. It provides for a tight closure between the under surfaces of the skylight plates and the yielding and movable supporting elements. The thin knife edges of the ridge 11 or 11', being 70 of lead, will readily flatten and accommodate itself to variations in the surface of the glass plates, whether they be smooth, corrugated, or otherwise. Being thus tightly embedded against the plates, the said ridges, 75 embodied with their gutter-providing portions, are thus so incorporated with the plates that they will adapt themselves and move with them, thus insuring the maintenance of such direct engagement between 80 the plates and supporting ridges, and preventing independent movement of the plates on their supports and thus unseating them, thereby obviating any danger of breakage.

The clamping construction and the various other features of the invention above described contribute to its efficiency in providing moisture-tight joints, a strong durable construction, prevention of breakage, and with ample facility for renewal or repair of 90 any of the several parts.

It will be understood that the invention may be variously changed or modified in its construction, design, proportions, or adaptations to particular conditions of use, 95 but that all such changes are within the province of the skilled mechanic, and the scope of the following claims.

What I claim is:

1. In skylight construction, the combination with a stationary supporting base, of a soft metal plate-supporting bar having a flat base slidably mounted on said base provided with an upwardly extending knife edge ridge, and a skylight plate resting on 105 said knife edge.

2. In skylight construction, the combination with a stationary supporting base, of a soft metal plate-supporting bar having a flat base slidably mounted on said base 110 provided with an upwardly extending knife edge ridge, a skylight plate resting on said knife edge, and a covering plate bearing on the upper surface of the skylight plate and pressing it against the knife edge ridge. 115

3. In skylight construction, the combination with a stationary supporting base, of a soft metal plate-supporting bar having a flat base slidably mounted on said base provided with an upwardly extending knife 120 edge ridge and an integral longitudinal flange extending upwardly from the base providing a gutter between the flange and said ridge, and a skylight plate resting on said knife edge.

4. In skylight construction, the combination with a stationary supporting base, of a soft metal plate-supporting bar having a flat base slidably mounted on said base provided with an upwardly extending ridge 125

having a compressible bearing edge adapted under pressure to intimately conform to and make adhering engagement with the skylight plate, and a skylight plate resting on and movable with said ridge.

5. In skylight construction, the combination with a stationary supporting base, of a soft metal plate-supporting bar having a flat base slidably mounted on said base 10 provided with an upwardly extending ridge having a compressible bearing edge adapted under pressure to intimately conform to and make adhering engagement with the skylight plate, a skylight plate resting on and 15 movable with said ridge, and a covering plate bearing on the upper surface of the skylight plate and pressing it against the bearing edge of said ridge.

6. In skylight construction, the combination with a stationary supporting base, of a soft metal plate-supporting bar having a flat base slidably mounted on said base provided with an upwardly extending ridge having a compressible bearing edge adapted 25 under pressure to intimately conform to and make adhering engagement with the skylight plate and an integral longitudinal flange extending upwardly from the base providing a gutter between the flange and 30 said ridge, and a skylight plate resting on said ridge.

7. In skylight construction, the combination with a stationary supporting base, of a soft metal plate-supporting bar having a flat base slidably mounted on said base provided with an upwardly extending knife edge ridge providing a compressible bearing edge adapted under pressure to intimately conform to and make adhering engagement with the skylight plate, and a 40

skylight plate resting on and movable with said ridge.

8. A soft metal plate-supporting bar of the class described having a flat base adapted to be slidably mounted on a bearing support and provided with an upwardly extending knife edge ridge. 45

9. A soft metal plate-supporting bar of the class described having a flat base adapted to be slidably mounted on a bearing support and provided with an upwardly extending knife edge ridge, and an integral longitudinal flange extending beyond the flat base. 50

10. A soft metal plate-supporting bar of the class described having a flat base adapted to be slidably mounted on a bearing support and provided with an upwardly extending knife edge ridge, and an integral longitudinal flange extending beyond the flat base and providing a gutter between 55 said flange and ridge. 60

11. The combination with the transverse roof member and the skylight plates thereon, of a cap member straddling the roof member having edge portions bearing on the upper faces of said plates and provided with central bolt holes surrounded by upwardly turned lips, interfitting clamps thereon having similar bolt holes and lips, bolts connected with the roof member extending through said cap and clamps, and securing nuts on the bolts having recessed under faces embracing the lips of said clamps. 65

In testimony whereof I hereunto affix my 70 signature in the presence of two witnesses.

THOMAS W. IRWIN.
